CHAIN CLEANING APPARATUS

Harry D. Lathrop, Chicago, Ill., assignor to The Lathrop-Paulson Company, Chicago, Ill., a corporation of Illinois

Application April 12, 1940, Serial No. 329,279

5 Claims. (Cl. 198—229)

This invention relates to cleaning and protection of conveyer chains and the like and, among other objects, aims to provide a simple and efficient apparatus for cleaning conveyers and conveying chains without interrupting operation.

The nature of the invention may be readily understood by reference to one illustrative apparatus embodying the invention and shown in the accompanying drawing.

In said drawing:

Figure 1 is an elevation of the apparatus taken longitudinally of a conveyer chain and showing a section of the latter; and Fig. 2 is an elevation of the apparatus taken transversely of the conveyer chain and showing a section of conveyer chain and a supporting guideway therefor.

Conveyers, and particularly conveyer chains, deteriorate and wear rapidly under the action of foreign substances which collect thereon during operation. The articles conveyed often deposit on the chains dust, particles of metal, and other substances which act like abrasives, particularly on link conveyer chains, or otherwise interfere with the conveyer. These abrasive materials are picked up and held on the links and particularly the socket portions because of the oil or other lubricant which is placed on each link. Unless promptly removed, such foreign substances mixed with the lubricant substantially shorten the life of the conveyer chain and particularly the socket portions of the links.

The illustrative apparatus provides means for effecting cleansing without interruption of operation of the conveyer. Jets of steam under substantial velocity are directed from a plurality of directions against the conveyer chain and other portions of the conveyer requiring cleaning. The action of the jets of steam is such that the cleaning is effected without reduction of speed of travel of the conveyer and simply by passing the conveyer chain or the like through the steam jets.

The conveyer is here represented by a single chain 10 comprising flexibly connected links 11. In this instance, the steam jets are directed against the chain from opposite directions by nozzles 12 whose width (see Fig. 2) is great enough to embrace the width of the conveyer chain. The nozzles are advantageously designed to develop a wide, thin jet of high velocity with a minimum of turbulence. As here shown, the nozzles 12 may be connected by pipes 13 with a common supply line 14.

The apparatus is preferably located at an idle

portion of the run of the conveyer chain so that the articles carried by the conveyer will not interfere with the cleaning operation. Preferably the chain is supported by a guide 15 in the form of a channel as it passes through the cleaning apparatus in order to hold the chain in a fixed relation to the nozzles. This permits the nozzles to be brought very close to the chain (without danger of collision of the chain with the nozzles), thereby increasing the efficiency of the steam jets. The nozzles are preferably arranged in relation to the chain to deliver the steam jets against the chain from the directions best calculated to remove foreign substances from the chain. In the particular chain illustrated, the jets are directed against the upper and lower faces of the chain links. Preferably the nozzles are relatively offset in the direction of travel of the chain so that there will be no tendency of the jets to impinge against or neutralize each other. It has been found that the use of a plurality of jets from different directions is much more effective in removing foreign substances and is much more economical in the use of steam than a single jet. The chain guide is also cut away as at 16 so as not to obstruct the free action of the steam jets.

The specific form of the nozzles and chain guide 15 depends, of course, on the character of the conveyer. For example, a double chain conveyer would require duplication of the nozzles as well as the guide.

When steam pressures of the order of one hundred pounds per square inch are employed, there is substantial superheating of the steam as it issues from the nozzle. This avoids condensation of moisture on the chain with attendant rusting.

If desired, the apparatus may be enclosed in an appropriate housing to reduce noise and prevent uncontrolled escape of steam. While the apparatus may be used continuously during operation of the conveyer, generally it need be put in operation only for such portion of the period of operation of the conveyer as is necessary to prevent harmful accumulation of foreign substances on the chain.

The cleaning device may be supported in any desired manner. In the illustrations given, it is shown supported by a bracket arm 17, extending from the frame 18 of a conveyor or other device.

The heat of the steam aids in breaking up the oily and gummy abrasive accumulations and the direct physical blasting force of the steam

strips the foreign material from the links and particularly from the socket portions thereof.

Obviously the invention is not limited to the details of the illustrative apparatus since these may be variously modified. Moreover, it is not indispensable that all features of the invention be used conjointly since various features may be used to advantage in different combinations and sub-combinations.

I claim:

1. In apparatus of the character set forth, a conveyor track, a conveyor carried by said track and guided thereon, a plurality of nozzles located in close proximity to the chain and adapted to deliver a cleaning fluid against the chain, said nozzles being located on opposite sides of the chain and offset longitudinally with respect to each other, said track having an opening therein in registry with said nozzles to permit free travel of the cleaning fluid through the chain. 20

2. In apparatus of the character set forth, a conveyor track equipped with bottom and side walls, said track having an opening therein, and at least two nozzles for directing a cleaning fluid against the chain, said nozzles being located on opposite sides of the chain and in close proximity thereto and being shaped to deliver against the chain a thin jet whose width is substantially that of the chain, the opening in said track being in registry with said jets to permit free travel of the cleaning fluid through the chain. 30

3. In combination, a conveyor track equipped with a bottom wall and side walls, a conveyor chain consisting of rectangular chain links equipped with interlocking ball and socket connections, a nozzle supported directly above said track in close proximity to the top of the chain

and adapted to direct cleaning fluid downwardly, and a second nozzle supported below said track to direct cleaning fluid upwardly against the bottom of said chain, said track being provided with a longitudinal opening through which cleaning fluid delivered from either of said nozzles may pass.

4. In combination, a conveyor track provided with a longitudinal opening in the bottom thereof, a conveyor chain comprising links which engage marginal portions in said track adjacent said opening so as to move over said opening, said links being provided with a central sprocket opening and with interlocking ball and socket connections, a nozzle supported above said chain, and a nozzle supported below said track, said nozzles being offset longitudinally and being in registry with said opening in the conveyor track so that the cleaning fluid may pass through said chain.

5. Apparatus for cleaning conveyer chains and the like comprising, in combination, a plurality of steam nozzles located in close proximity to the chain at an idle portion of the run of the chain, said nozzles being shaped to deliver against the chain a thin steam jet whose width is substantially that of the chain, a guide for supporting said chain in fixed relation to said nozzles as the chain traverses the steam jets, said nozzles being located on opposite sides of the chain and in close proximity thereto and being offset longitudinally of the chain so that the steam jets do not impinge against each other, said guide having an opening therein in register with said jets to permit free travel of the steam jets through the chain. 35

HARRY D. LATHROP.
